ELEVATOR CABLE EQUALIZER

Severn A. White, Baltimore County, Md.

Application March 13, 1936, Serial No. 68,775

4 Claims. (Cl. 187—1)

The present invention relates to new and useful improvements in elevators in general and has for its primary object to provide, in a manner as hereinafter set forth, novel means for connecting the multiple cables of an elevator to the car and weights in a manner to maintain a uniform load at all times on the several cables.

Another very important object of the invention is to provide an equalizer of the aforementioned character embodying a construction and arrangement which is such that crystallization of the cables from twisting and untwisting will be materially reduced or substantially eliminated.

Other objects of the invention are to provide an elevator cable equalizer of the character described which will be comparatively simple in construction, strong, durable, highly efficient and reliable in use, compact, and which may be manufactured and installed at low cost.

All of the foregoing and still further objects and advantages of the invention will become apparent from a study of the following specification, taken in connection with the accompanying drawings wherein like characters of reference designate corresponding parts throughout the several views, wherein:—

Figure 1 is a view in side elevation of an installation embodying the present invention, the cross beams on the roof of the car being shown in cross-section.

Figure 2 is a view in horizontal section, taken substantially on the line 2—2 of Figure 3.

Figure 3 is a vertical sectional view, taken substantially on the line 3—3 of Figure 2.

Figure 4 is a fragmentary view in vertical section, taken substantially on the line 4—4 of Figure 2.

Figure 5 is a detail view in bottom plan of the rockable lower plate.

Figure 6 is a detail view in bottom plan of the stationary upper plate.

Referring now to the drawings in detail, it will be seen that the reference numeral 1 designates a plurality of cables to one end of which the usual weights 2 are connected. Connected to the other ends of the cables 1 is the car 3. Extending across the top of the car 3 is a pair of spaced, parallel beams 4.

The embodiment of the invention which has been illustrated comprises a stationary upper plate 5 of suitable metal having a substantially conical lower face 6 on the apex of which is an integral ball 7. Mounted beneath the plate 5 is a rockable plate 8 having formed in its upper face a socket 9 for the reception of the ball 7.

It will thus be seen that the plate 8 is mounted for universal rocking movement on the plate 5. The plate 8 further includes reinforcing webs 10.

Depending from the lower face of the rockable plate 8 is a plurality of integral balls 11 on which cross-heads 12 are rotatably and rockably mounted. The cross-heads 12 have formed therein, at intermediate points, sockets 13 which accommodate the balls 11. In their end portions the cross-heads 12 have formed therein openings 14 for the passage of vertical rods 15.

Plates 5 and 8 have openings 16 and 17, respectively, therein through which the rods 15 pass. At their upper ends the rods 15 terminate in 15 sockets or the like 18 in which the ends of the cables 1 are anchored. The lower end portions of the rods 15 are threaded to receive nuts 19. Interposed between nuts 19 and the cross-heads 12 are ball washers 20. The reference numeral 21 designates lock nuts for the nuts 19.

When the equalizers are installed the upper plate 5 is secured in any suitable manner, as at 22, beneath the beams 4 of the car 3 and to a suitable attaching structure 23 on the weights 2. 25 As is believed to be obvious, the construction and arrangement is such that the load will be equally distributed at all times on the cables 1 by reason of the fact that the plate 8 and cross-heads 12 are capable of substantially universal rocking 30 movement. Further, the ball washers 20 permit the rods 15 to rotate freely thereby allowing the cables 1 to twist and untwist under stress, as when starting and stopping, thus substantially eliminating crystallizing. Any suitable 35 means may, if desired, be provided for lubricating the moving parts of the device.

It is believed that the many advantages of an equalizer constructed in accordance with the present invention will be readily understood and 40 although a preferred embodiment of the device is as illustrated and described, it is to be understood that changes in the details of construction and in the combination and arrangement of parts may be resorted to which will fall within the scope 45 of the invention as claimed.

What is claimed is:—

1. An elevator cable equalizer comprising a stationary plate, a second plate mounted for universal rocking movement beneath said stationary plate, cross-heads rockably mounted beneath the second named plate, and means for connecting the cables to said cross-heads. 50

2. An elevator cable equalizer comprising a stationary plate, a second plate mounted for uni- 55

versal rocking movement beneath said stationary plate, cross-heads rockably mounted beneath the second named plate, and means for connecting the cables to said cross-heads, said means including rods rotatably connected to the cross-heads and extending upwardly therefrom through the first and second named plates.

3. An elevator cable equalizer comprising a stationary plate, a second plate mounted for universal rocking movement beneath said stationary plate, a plurality of balls on the lower side of the second named plate, cross-heads rotatably and rockably mounted on said balls, and rods connected to said cross-heads on opposite sides of the balls and extending upwardly therefrom through the first and second named plates for connection with the cables.

4. An elevator cable equalizer comprising a stationary plate, a ball integral with the lower side

of said stationary plate, a second plate mounted for substantially universal rocking adjustment beneath the stationary plate, the second named plate having a centrally located socket therein accommodating the ball, a plurality of balls integral with the lower side of the second named plate, cross-heads rotatably and rockably mounted on the second named balls, said cross-heads having sockets therein at intermediate points accommodating said second named balls, rods extending slidably and rotatably through the first and second named plates and through the end portions of the cross-heads, nuts threaded on the lower end portions of said rods, ball washers interposed between said nuts and the cross-heads, and means on the upper ends of the rods for anchoring the cables thereto.

SEVERN A. WHITE.
